UNITED STATES PATENT OFFICE.

RUBEN C. M. HASTINGS AND THURSTON MATHENY, OF ATHENS, OHIO.

LOCK-OUT DEVICE FOR TELEPHONES.

No. 856,146.

Specification of Letters Patent.

Patented June 4, 1907.

Application filed May 7, 1906. Serial No. 315,712.

To all whom it may concern:

Be it known that we, RUBEN C. M. HASTINGS and THURSTON MATHENY, citizens of the United States, residing at Athens, in the 5 county of Athens and State of Ohio, have invented a new and useful Lock-Out Device for Telephones, of which the following is a specification.

This invention relates to telephone systems, 10 and has for one of its objects to provide means of simple construction whereby a selective signal may be sent along a party line for the purpose of sounding a call bell or other calling apparatus of the selected subscriber 15 only, the remaining bells being prevented from operating.

A further object of the invention is to provide an apparatus of this kind in which a mechanism of simple construction is employed 20 for engaging and locking the bell clapper rods at non-selected stations, and in which all of the clapper rods are initially locked, only one of such rods being movable to release position at one time.

25 A still further object of the invention is to provide a selective system in which all but the calling and the called subscribers may be locked out, thus rendering it impossible for any other station to overhear the conversation.

30 A still further object of the invention is to provide a receiver hook lock of simple construction which may be brought to locking position by the calling subscriber at will in order to lock out and prevent movement of the receiver hooks at all except the connected stations.

With these and other objects in view, as will more fully hereinafter appear, the invention 40 consists in certain novel features of construction and arrangement of parts, herein-after fully described, illustrated in the accompanying drawings, and particularly pointed out in the appended claims, it being understood that various changes in the form, proportions, size and minor details of the structure may be made without departing from the spirit or sacrificing any of the advantages of the invention.

45 In the accompanying drawings:—Figure 1 is a front elevation of a switch box of a telephone, the door being shown in open position, and illustrating the arrangement of the clapper locking mechanism and circuit controlling devices. Fig. 2 is a perspective view of the switch box showing the mechanism on

the exterior of the box. Fig. 3 is a vertical section on the line 3—3 of Fig. 1. Fig. 4 is a detail elevation of the clapper rod lock and its controlling devices, showing the clapper 60 rod locked from movement. Fig. 5 is a similar view, showing the clapper rod released. Fig. 6 is a sectional plan view on the line 6—6 of Fig. 1, showing the connection between the external operating mechanism and the 65 inner contacts. Figs. 7 and 8 are elevations of the switch hook lock, Fig. 7 showing the receiver hook released, and Fig. 8 illustrating it in locked position. Fig. 9 is a diagram showing the selecting and lock out 70 circuit.

Similar numerals of reference are employed to indicate corresponding parts throughout the several figures of the drawings.

In carrying out the invention, each of the stations of a party line is provided with a switch box A arranged to contain a magneto generator B of the usual construction, and extending into the box is a receiver hook C 80 which operates in the usual manner to close the talking circuit when the receiver is removed from the hook. The construction of this portion of the mechanism, the local wiring of the talking and calling circuits, and 85 the main line circuits, form no part of the present invention and may be of the usual type, the system being adapted for use in connection with the ordinary bridging bell, series or other party line circuits.

90 On the door D of each switch box is secured a polarized call bell E of ordinary construction, and to the armature of this bell is secured a clapper rod F, also of the usual type.

The door D is provided with a bearing or support for a short horizontal shaft 10 that is provided at its outer end with a hand or pointer 11 arranged to move over a numbered dial 12, the latter being preferably arranged within a suitable casing having a transparent panel 15.

95 The inner end of the shaft 10 is supported by a bridge 17 that is secured to the inner face of the door, or to a suitable base plate 18 carried by said door. This shaft carries a notched disk 19 and a ratchet wheel 20, one having notches, and the other teeth of a number equal to the graduations of the dial 12.

100 The ratchet wheel 20 is engaged by a tooth 21 of a pawl bar 22 that is hung from one end

75

90

95

105

110

of an armature lever 23 pivoted on a suitable stud 24, a spring 25 being employed to retain the pawl bar in contact with the ratchet wheel. The lever 23 carries an armature 26 that is disposed within the field of force of a pair of electro-magnets 27 that are connected in the selecting circuit, and each time the latter is energized the armature 26 will be attracted and the ratchet wheel will be rotated to the extent of a single tooth, advancing the pointer one graduation on the dial.

The disks 19, of which there is one at each station, are all of precisely the same construction, each being provided with recesses 29, any one of which may receive the shank of a cam 30, the cams being interchangeable, and being disposed at different points in the respective disks, so that as all of the disks throughout the system simultaneously receive a step by step movement, the different cams will be successively brought to operative position, the cam of station number 1 first moving to operative position, and then on the second movement, the cam of station number 2, and so on throughout the whole number of connected stations. At a point below the clapper rod is a pivotally mounted locking lever 32, having at one end a notched recess 33 for the reception of the clapper rod, and when the parts are in the position shown in Fig. 4, which is the normal position throughout the system, all of said clapper rods will be locked, and held from vibratory movement to an extent sufficient to sound the bells. When the lever moves to the release position shown in Fig. 5, a single clapper rod is released, and the bell at that station will be sounded when the signaling current is sent over the line. At a point adjacent to the disk 19 is a cam actuated lever 34, the free end of which rests by gravity on the periphery of the disk. This lever is connected at a point intermediate its ends to a link 35 that is hung from the lever 32. The lever 34 is disposed in the path of movement of the cam block 30, and as the latter rotates said lever 34 will be raised and the notched end of lever 32 will be depressed to release the clapper rod, this operation occurring first at station No. 1, then at station No. 2, and so on as the disks are simultaneously rotated; the operator holding the apparatus at clapper rod releasing position at the station which he desires to call, and then sending the calling current over the line by operating his magneto generator.

Each of the doors D is further provided with a bearing for a short shaft or arbor 40 that carries at its outer end a handled crank 41 which is grasped by the operator, and pulled down until it strikes the pin 43, (see Fig. 2), which forms a stop for limiting the movement of the crank in one direction. To the inner end of the shaft 40 is secured a rocker arm 45 to which is connected a spring

46 tending to hold the arm in the position shown in full lines in Fig. 1. This arm is provided with a recess intermediate its ends, and into said recess extends one arm of a contact lever 48 that is pivoted on a stud 49, and is arranged to alternately engage two contacts 50 and 51, the spring 46 normally holding the parts in such position that the contact 48 will be in engagement with the contact 50. This will maintain the selecting and lock out circuit closed, but disconnected from the batteries or other source of energy. When the crank 41 is moved to its lowest position, the arm 45 moves to the dotted line position shown in Fig. 1, and the contact 48 is then thrust into engagement with the contact 51, closing the circuit at the calling station with the local battery of said calling station, and thus energizing the entire line.

At the left hand side of the switch box is arranged a pivoted dog 50' having a bifurcated end which straddles the receiver hook. The rear face of this dog is flattened, as indicated at 51', and is arranged to be engaged by a locking bar 52 which carries an armature 53 disposed in the field of force of a pair of lock out electro-magnets 54, and when these magnets are energized, the armature will be attracted and the locking bar will be raised to the position shown in Fig. 8 preventing the movement of the dog 50 to an extent sufficient to allow the receiver hook to rise and close the talking circuits. These parts are preferably arranged within a suitable protective casing 55 at one side of the switch box, or they may be arranged inside the switch box proper, if desired.

Fig. 9 illustrates the selecting and lock out circuit only, all of the talking and signaling wires having been purposely omitted in order to avoid confusion.

It has been found desirable to employ means for automatically locking the arm 45 in the position to which it is moved at the completion of a signaling operation in order that the line may be kept energized, and the receiver hooks of the subscribers at all stations held in locked position with the exception of the calling and called station. For this purpose an additional lever 56 is pivoted on a stud 57 carried by the door of the switch box, and is provided with a depending hook 58 that is arranged to extend under the receiver hook, so that when the latter is held depressed by the weight of the receiver, the arm 56 will be held down out of the path of movement of a lug or shoulder 59 that is carried at the lower end of the arm 45, and the latter is free to play between the dotted and full line positions of Fig. 1. If the receiver is removed from the hook, the lever 56 is pulled upward by its spring 56', and the end of the lever is then placed in the path of movement of the lug or shoulder 59, so that the arm is held in the dotted line position with the con-

tacts 48 and 51 in engagement with each other, thus maintaining the circuit energized.

The selecting and lock out wire 60 may extend from ground at one end of the system 5 through the lock out electro-magnet 54 at station number 1, then through the selecting magnets 27 at the same station, thence by wire 61 to the contact arm 48, thence contact 50, wire 62, and again by wire 60 to station 2, 10 where it is connected in similar manner, and thence on for as many stations as there are in the line, passing finally to ground at the last station, or, if necessary, a metallic return wire may be employed instead of the ground.

15 At a suitable point in the system the wire 60 is connected in series with an electro-magnet 65 of low resistance, and after leaving this electro-magnet the circuit may be traced through the bell crank lever 66, contact 67, 20 and wire 68 to the wire 60. The bell crank lever 66 has at one end a pin 69 that extends through a slot in a pivoted lever 70 carrying an armature 71 that is disposed within the field of force of the electro-magnet 65. 25 When this electro-magnet is energized, and the armature attracted, the bell crank contact 66 moves from engagement with contact 67 into engagement with a contact 72, closing a circuit which connects a large battery 73 in series with the selecting and lock out line. At each of the subscriber's stations is a local battery 74, which, if necessary, 30 may constitute the battery of the primary circuit. This battery is connected by a wire 35 75 to the contact 51 on one side, and by the wire 76 to the wire 60 on the opposite side.

It will be seen that in the normal position of the parts, the selecting and lock out circuit is not energized and any of the receiver hooks 40 may be raised while all of the clapper rods of the call bells are locked from movement.

Any subscriber along the line wishing to call another, say number 5 for instance, pulls down on the handled crank 41. This moves 45 the contact arm 48 of the calling subscriber's station from contact 50 to contact 51 and connects the calling subscriber's local battery in series with all of the electro-magnets along the line, including the electro-magnet 65, 50 and as the latter is wound to low resistance, its armature 71 will be attracted, moving the bell crank contact 66 into engagement with the contact 72, thus connecting the large battery 73 also in series with the electro-magnet, 55 so that if the local battery is not of sufficient strength to properly energize all of the magnets the throwing on the extra current will accomplish the desired result and all of said electro-magnets will be energized. This results in operating the pawl bars 22 at every 60 station along the line, and all of the disks 19 will be turned one step, and all of the cams or pointers may be advanced to the extent of one revolution. At the same time the cam 65 block of station number 1 will pass under the

lever 34 and raise the latter to effect the lowering of the notched end of lever 32, thus releasing the clapper rod of the call bell at station number 1. At the same time all of the electro-magnets 54 will be energized and the 70 locking devices of every station will be brought into play, locking all of the receiver hooks from movement. This operation is repeated five times, until the cam block 30 at number 5 station elevates the lever 34, and 75 through lever 32 releases the clapper rod at station number 5.

The calling subscriber now holds the lever 41 at the completion of the fifth movement, and by operating his magneto generator, the 80 calling current is sent along the line in the usual way, and the electro-magnets of all of the call bells are energized, but as all of the clapper rods except that belonging to station number 5 are locked, all will remain silent except that of station number 5. After sending the signal, the crank is allowed to move to its normal position, thus disconnecting the batteries from the line, and allowing the electro-magnets of the receiver hook locks to be 85 deenergized, so that the subscriber at station number 5 may remove his receiver from the hook, and the calling subscriber may, also, remove his receiver. This being done, the crank may be again pulled down, 90 if desired, for the purpose of reenergizing all of the electro-magnets 54, so that all of the receiver hooks except those of the connected subscribers will be positively locked and eaves-dropping prevented. When this last 95 movement occurs, the lug or shoulder 59 of the arm 45 will be thrown beyond the end of the lever 56 and will be automatically locked from return movement so that the line will be held energized and all of the receiver hooks, 100 except those of the calling and called subscribers, will be held locked. This latter operation may be performed by either of the connected subscribers, but will usually be the 105 duty of the called subscriber, who, in this manner notifies the calling subscriber that he has removed his receiver hook, the additional closing the circuit causing the advancement of the hands or pointers of all 110 dials to the extent of another graduation. 115

The armature lever 53 may be provided with a busy signal 100, which, when the armature is attracted to locking position, will be exposed through a display opening in the casing. 120

We claim:—

1. In party line telephone systems, a call bell arranged at each station, a locking device engaging the clapper rod of the bell, an electro-magnetically actuated means for releasing said locking device, a normally closed deenergized selecting circuit in which all of the electro-magnets are connected, a local battery at each station, means for connecting the batteries in the selecting circuit, an aux- 125

iliary battery, and means for automatically connecting the battery in the circuit whenever the local battery is thrown on the line.

2. In party line telephone systems, a call bell at each station, a pivoted lever having a notch for the reception of the clapper rod of the bell, an electro-magnet, an armature disposed within the field of force of the electro-magnet, a pivoted armature carrying lever, a pawl carried by said lever, a ratchet wheel with which said pawl engages, a cam lever movable with the ratchet wheel, a cam actuated lever, means for connecting the same to the clapper rod locking member, and a manually operable means at each station for making and breaking the circuit.

3. In party line telephone systems, a call bell at each station, a clapper rod locking lever, an electro-magnet, an armature arranged within the field of force of the electro-magnet, an armature carried lever, a pawl operated thereby, a ratchet wheel with which the pawl engages, a revoluble disk having a notched periphery, a cam block adjustable into any one of the notches, a cam actuated lever adjacent to the disk, means for connecting the cam lever to the locking lever, a selecting line in which all of the electro-magnets are connected, and means at each station for energizing and deenergizing the line.

4. In party line telephone systems, a receiver hook at each station, a receiver hook locking device, an electro-magnet for operating the same, a normally closed deenergized circuit in which all of the electro-magnets are connected, a local battery at each station, a

manually operable means for connecting the battery in the circuit, and means under the control of each receiver hook for retaining the line closed and energized.

5. In party line telephone systems, a receiver hook at each station, an electro-magnetically operated receiver hook locking device, a normally closed deenergized circuit in which all of the electro-magnets are connected, a local battery at each station, a switch for connecting the battery in the line, a switch operating arm having a shouldered end, a spring elevated lever movable in the path of the shoulder to hold the circuit closed and energized, and a hook depending from the lever and arranged to extend under the receiver hook.

6. In a party line telephone system, a selecting line, selecting mechanism at each station, said line being normally closed and deenergized, a local battery at each of the stations, means at each station for connecting the battery in the line, a main line battery normally disconnected from the line, and an electro-magnetically actuated means connected in the line and adapted when energized by the local battery to connect the main battery in series in the line.

In testimony that we claim the foregoing as our own, we have hereto affixed our signatures in the presence of two witnesses.
